UNITED STATES PATENT OFFICE.

WILLIAM THOMAS OWEN, OF ROLAND PARK, MARYLAND, ASSIGNOR TO FOSTORIA
GLASS COMPANY, OF MOUNDSVILLE, WEST VIRGINIA, A CORPORATION OF WEST
VIRGINIA.

DESIGN FOR A GLASS VESSEL.

44,381.

Specification for Design.

Patented July 22, 1913.

Application filed February 12, 1913. Serial No. 747,986. Term of patent 14 years.

To all whom it may concern:

Be it known that I, WILLIAM THOMAS OWEN, a citizen of the United States, and residing at Roland Park, in the county of Baltimore and State of Maryland, have invented a certain new, original, and ornamental Design for a Glass Vessel, in the accompanying drawing a superficially-ornamented glass vessel being shown.

No novelty is claimed herein for the shape of the vessel.

I claim:

The ornamental design for a glass vessel, as shown.

WILLIAM THOMAS OWEN.

Witnesses:

MARK N. DAVIS,
ELLIS BERMAN.
